UNITED STATES PATENT OFFICE.

RALPH R. KIMBALL, OF CHICAGO, ILLINOIS, ASSIGNOR TO THE KIMBALL & CHAPPELL COMPANY, OF CHICAGO, ILLINOIS, A CORPORATION OF ILLINOIS.

DESIGN FOR A BED.

49,665.

Specification for Design.

Patented Sept. 19, 1916.

Application filed July 3, 1916. Serial No. 107,471. Term of patent 3½ years.

To all whom it may concern:

Be it known that I, RALPH R. KIMBALL, a citizen of the United States, residing at Chicago, in the county of Cook and State of Illinois, have invented a new, original, and ornamental Design for Beds, as shown in the accompanying drawing and described in the following specification.

In the drawings: Figure 1 is a perspective view of the bed showing my new design. Fig. 2 is a view in elevation enlarged, of one of the ornamental urns. Fig. 3 is a view in elevation enlarged, of one of the ornamental corners.

The design comprises the head and foot grilles connected by the side-rails, each of the grilles comprising the corner posts 10, cross-rails 11 and 12, and fillers 13, all constructed of square tubing.

The corner posts 10 and the cross rail 11 are connected at the upper corners by ornamental corners 14, while one of the fillers, as 15, is shorter than the fillers 13 and a cross-bar 16 is employed with an ornamental urn 17 set into the space formed between the bar 16 and top rail 11. As in the drawing on the scale of Fig. 1 it is impossible to show the ornamental effect of the urn and corners it has been found necessary to employ additional figures enlarged to show these two ornamental features.

I claim:

The ornamental design for a bed as shown and described.

RALPH R. KIMBALL.
